UNITED STATES PATENT OFFICE.

JOHN B. GURY, OF ST. LOUIS, MISSOURI.

VISE.

SPECIFICATION forming part of Letters Patent No. 499,291, dated June 13, 1893.

Application filed January 25, 1893. Serial No. 459,677. (No model.)

To all whom it may concern:

Be it known that I, JOHN B. GURY, of St. Louis, Missouri, have made a new and useful Improvement in Vises, of which the following is a full, clear, and exact description.

The present improvement is adaptable to various forms of bench and other vises, and especially to vises used in connection with milling and planing machines, and it consists mainly in the means whereby the movable jaw is adapted to be readily and rapidly operated, and to be opened widely, and when closed to be easily and securely tightened upon the object to be clamped, all substantially as is hereinafter set forth and claimed, aided by the annexed drawings, making part of this specification, in which—

Figure 1 is a view in perspective of the improved vise; Fig. 2 a plan of the same; Fig. 3 a vertical, longitudinal, central section of the same; Fig. 4 a bottom view; Fig. 5 a vertical cross section on the line 5—5 of Fig. 3; Fig. 6 a view in perspective of the movable jaw; Fig. 7 a view in perspective of the fixed jaw; and Fig. 8 a side elevation of the screw.

The same letters of reference denote the same parts.

A represents the fixed jaw of the construction. It is attached to the bed-plate, B, and in practice it can be made in one piece therewith, substantially as shown. The jaw may have a suitable face-place, a, which is held in place by means of the bolts a', and a² a² represent strengthening ribs, and a³, a³, are perforated lugs to provide for attaching the vise to any suitable support.

C represents the movable jaw. It is adapted to be moved upon the bed-plate toward and from the fixed jaw, as indicated by its positions shown in the full and in the broken lines, respectively, in Fig. 3. It is operated by means of the screw D, and in its movement it is guided by means of the bar or plate E. The last named part extends longitudinally upon the bed-plate, and preferably from end to end thereof, and is suitably secured thereto, and, to fully carry out the improvement, it is swiveled to the bed-plate to be turned laterally thereon, as indicated by its different positions shown in broken lines in Fig. 2, and its end, e, works in a socket, a⁴, in the fixed jaw, and at its opposite end the part

is provided with a threaded bearing, e', to receive the screw, D, which in operating the movable jaw is worked forward and back 55 therein in the manner presently described.

F represents the bearing upon which the guide-bar E is swiveled. Its preferable form is shown as being a bolt inserted from beneath in the bed-plate and extending upward into 60 the guide bar, and having its upper end, f, threaded to be screwed into the guide bar. The guide-bar carries the movable jaw and the screw D with it in its lateral adjustment, and it can be fastened as desired so as to 65 cause the movable jaw to be presented at the preferred angle to the fixed jaw by means of the tightening bolt G which works through the slot, b, in the bed-plate and is threaded at g, to be screwed into the guide-bar, substantially as shown. The guide-bar is prefer- 70 ably of the dove-tail form shown in cross section and the movable jaw is correspondingly shaped in its under side to engage therewith, and the movable jaw may have a suitable wear-plate, c, which takes the lateral wear upon the jaw. The movable jaw also may have a face-plate, c', which is held in place by the bolts c², as shown. The leading

feature, however, of the improvement is the 75 means for opening and closing the movable jaw. The screw D, is double-threaded, having a right hand threaded portion, d, which engages in the bearing e', and a left hand threaded portion, d', which engages, at c³, with 80 the movable jaw. The rotation of the screw, D, therefore causes the screw to be moved endwise in the bearing e', and the movable jaw to be moved endwise upon the screw. The result is the jaw is rapidly opened apart 85 from and closed toward the fixed jaw. The movable jaw can also be opened widely, as indicated in Fig. 3. To provide for this the jaw may be recessed as shown at c⁴, or otherwise shaped, to pass the bearing, e'. The 90 movable jaw is also suitably shaped to admit the screw and the chamber, c⁵, into which the end of the screw, in the present instance, passes, may be enlarged in order to lighten the jaw.

An additional feature of the improvement is making the thread in the portion d finer than is the thread in the portion d' of the screw D. By this means, after the movable

jaw is about to be closed, by a slight turn of the screw the jaw can be made to securely clamp the object being held in the vise. The screw D, is provided with a suitable crank, 5 d^2 , to enable it to be readily turned. In this manner it will be seen that the movement of the movable jaw is greatly facilitated, the capacity of the vise is increased, and the work is securely held, and at the same time the 10 vise is adapted for holding irregular or tapered objects as well as flat ones of uniform diameter or cross section.

I claim—

1. The combination of the bed plate having 15 at its end the fixed jaw, and perforated to admit a set screw to swivel the guide bar of the movable jaw, and slotted to admit a screw on which the guide is laterally movable, and the movable jaw and the double threaded screw 20 operating the same, and the threaded bearings for the screw to be moved in.
2. In combination with the bed plate having at its end the fixed jaw recessed for the 25 end of the guide bar, to allow its movements on its swiveled and slotted connections with the bed plate, the movable jaw and its double

threaded screw operating in bearings in the movable jaw, and in the outer end of the guide bar, said screw threads being finer at one end than at the other, substantially as de- 30 scribed.

3. The combination with the bed plate and fixed jaw, of the guide bar, dovetail in form and the movable jaw having a dovetail socket for the guide plate, and the screw for operating the movable jaw substantially as set forth. 35

4. In combination with the bed plate and the fixed jaw, the guide bar secured thereto, as described, and having at its outer end the bearing e' , and dovetail in form, and the movable jaw having a dovetail recess by which it fits to and moves on said guide bar, and a recess c^4 , to fit upon and over the bearing e' , when the movable jaw is fully drawn back, substantially as described. 40 45

Witness my hand this 7th day of January, 1893.

JOHN B. GURY.
